US00D754152S

(12) **United States Design Patent**
Kim et al.

(10) **Patent No.:** **US D754,152 S**
(45) **Date of Patent:** ** Apr. 19, 2016

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventors: **Jae Jeong Kim**, Seoul (KR); **So Young Yun**, Seoul (KR)

(73) Assignee: **Samsung Electronics Co., Ltd.,**
Suwon-si (KR)

(**) Term: **14 Years**

(21) Appl. No.: **29/495,456**

(22) Filed: **Jul. 1, 2014**

(30) **Foreign Application Priority Data**

Jan. 3, 2014 (KR) 30-2014-0000519

(51) **LOC (10) Cl.** **14-04**

(52) **U.S. Cl.**

USPC **D14/485**; D14/486

(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design. The broken lines are for environmental purposes only and form no part of the claimed design.

The dot-dash lines in the FIGURE illustrate a boundary line and form no part of the claimed design.

1 Claim, 1 Drawing Sheet
